UNITED STATES PATENT OFFICE.

MICHAEL J. CONTER, OF PARK RIDGE, ILLINOIS.

BOOKMARK.

Application filed March 18, 1922. Serial No. 543,162.

To all whom it may concern:

Be it known that I, MICHAEL J. CONTER, a citizen of the United States, residing in Park Ridge, in the county of Cook and State 5 of Illinois, have invented certain new and useful Improvements in Bookmarks, of which the following is a specification, reference being had to the accompanying drawings, forming a part thereof.

10 The purpose of this invention is to provide an improved construction of an automatic book-mark, that is, a device adapted to be engaged with some portion of the book and extend between the leaves for keeping the 15 place of the reader as adapted to pass from leaf to leaf automatically, as the leaves are turned by the reader. It consists in the elements and features of construction shown and described, as indicated in the claims.

20 In the drawings:—

Figure 1 is a perspective view of an open book equipped with a book mark embodying this invention.

Figure 2 is an axial section of the body 25 of the device embodying this invention upon an exaggerated scale.

Figure 3 is a section at the line 3—3 on Figure 2.

Figure 4 is a dissected view showing the 30 main member of the device and associated parts in side elevation.

Figure 5 is a view similar to Figure 2, showing a modification.

Figure 6 is a sectional view at the same 35 plane as Figure 2, showing a preferred way of placing the device in the book for use.

In the drawings, the body or assembled leaves of the book with which the device is shown in use is indicated at A, the side covers, B, B, and the back of the cover, or connection between the side covers, at B¹, and the body of leaves as bound together and lying open at C. The device embodying the invention comprises, as shown in the drawings, a tubular housing, D, in which there is mounted and journaled a spindle having at one end a head rabbeted or reduced in diameter to form a journal at D¹, by which the spindle is rotatably mounted in the 40 housing, and a flange head, D², by which the spindle is stopped endwise in one direction on the end of the housing. At the other end the housing has a closure, F, which may be screwed into the housing, D, as shown, to a 45 stop flange, F¹, with which it is provided so that it may be screwed tight. The closure

has a central aperture for journaling the spindle, E, and the spindle extending through that aperture is reduced and threaded to a shoulder, e, tightly against which a 50 securing nut, G, may be set, said nut lapsing on the margin of the journal aperture of the closure for stopping the spindle endwise in the opposite direction from that in which it is stopped by the head flange, D², 55 at the opposite end of the housing. H is a spring coiled around the spindle, E, having one end engaged with the spindle and the other end with the housing, the engagement with the housing being by the inner 60 end of the spring bent paraxially as seen at h, and entering the paraxial aperture in the closure, F. At the other end the spring is engaged with the spindle by engagement with the head. In the form shown in Figure 2, the coiled spring is made of one piece 65 of wire with the spring finger, J, hereinafter more particularly described, and the engagement of the coiled spring with the end piece is effected by a paraxial portion, h¹, of the 70 spring, which is formed between the forward portion and the radially extending portion which constitutes the spring finger, J. In this form the paraxial groove, d¹, in 75 the journaling portion of the head, D¹, affords lodgment for said paraxial portion, h¹, of the spring, and the spring finger, J, extends out radially through a sectoral radially extending notch, d², whose sectoral 80 extent limits the swing of said spring finger, J. In this form the paraxial groove, d¹, in 85 the journaling portion of the head, D¹, affords lodgment for said paraxial portion, h¹, of the spring, and the spring finger, J, extends off substantially at right angles with the axis of the 90 housing, but normally trending somewhat inwardly, that is, at an acute angle to the axis, so as to insure the lapsing of the 95 indent end, J¹, on the face of the book. Said end, J¹, is bent at an acute angle to the finger, inward toward the back, B¹, C, of the book, so that as the leaf on which it rests 100 is lifted for turning it as the reader advances, the leaf easily clears the finger without crowding the latter off from its lodgment, so that it remains lodged on the next leaf after the preceding leaf has been turned.

In Figure 5 there is shown a modification consisting in making the spring finger, J, not integral with the coiled spring, H, but instead, terminating the coiled spring at the outer end in the same manner in which it is 110 terminated at the other end, that is in a paraxially extending short portion, a², for

engagement of which the head, E, is suitably bored paraxially, and securing the end of the finger, J, in said head in a radial bore, as seen in said figure.

5 I do not limit myself to the particular or detail construction shown and described, since it is obvious that various methods of securing the coiled spring and the spring finger, various methods of providing for the 10 endwise stopping and journaling of the spindle in the housing, will be within the ordinary skill of any mechanic undertaking to make such a device, but the particular devices, details of construction and expedients 15 shown and described are regarded as advisable, and certain of them are specifically claimed.

K is a spring clasp finger which is secured to the upper end of the housing, D, and extends along the outside of the housing for 20 clasping the device in place on the book with the housing inserted between the back, B¹, and the body, C, of the book and the clasp- 25 ing finger engaged preferably between the leaves of the body of the book, as seen in Figures 1 and 6. The clasp finger, however, may be engaged with the back, B, as seen in Figure 2, without materially changing the mode of operation of the device.

30 I claim:-

1. An automatic book-mark comprising a tubular housing adapted to be inserted between the back of the cover of the book and the body of leaves thereof, and means by 35 which it is grasped to the book; a spindle journaled and longitudinally stopped in said housing; a spring coiled about the spindle in the housing and reacting between the spindle and the housing for rotating or rock- 40 ing the spindle in one direction; means for limiting such rocking movement, and a spring finger extending radially from the head of the spindle at one end of the housing having its extremity bent inward for 45 lapping the leaves of the book.

2. In the construction defined in claim 1, foregoing, the spindle having its head at the end from which the spring finger extends reduced to form a journal for the spindle in the housing, and a stop shoulder, for end- 50 wise stopping, the other end of the housing having a closure apertured to form a journal bearing for the spindle, said spindle being extended therethrough and reduced and threaded, and a nut screwed onto the reduced end to the shoulder and stopping the spindle endwise against the closure in the opposite direction from that in which the head of the spindle stops it at the other end. 55

3. In the construction defined in claim 1, foregoing, the housing having a closure at the end opposite the head, said closure having a paraxial aperture and the spring having its inner end bent for projecting into such aperture, said spring being normally 60 coiled so as to require compression axially for enclosure in the housing; whereby the spring may be inserted in the housing and engaged at its inner end with the closure 65 before the insertion of the spindle there- 70 through.

4. In the construction defined in claim 1, foregoing, the coiled spring and the radially extending figure being an integral piece of wire bent to form a portion extending par- 75 axially of the spring between the coil and the finger, the end of the housing from which the spring finger extends having a segmen- 80 tally extending notch for limiting the swing of the spring finger; and the journaled por- 85 tion of the head of the spindle having a par- axially extending notch for lodgment on the said paraxially extending portion of the spring, whereby the spring is rotatively engaged with the spindle at that end. 85

In testimony whereof, I have hereunto set my hand at Chicago, Illinois, this 9th day of March, 1922.

MICHAEL J. CONTER.
